By *Brundage* ATTORNEYS:

UNITED STATES PATENT OFFICE.

JOSEPH JANES, OF SOMERVILLE, MASSACHUSETTS, ASSIGNOR TO G. CLAY COX, OF ROCHESTER, NEW YORK.

CIRCUIT BREAKER FOR PHONOGRAFS.

Application filed June 21, 1922. Serial No. 569,916.

To all whom it may concern:

Be it known that I, JOSEPH JANES, of Somerville, in the county of Middlesex and State of Massachusetts, a citizen of the 5 United States, have invented a new and useful Improvement in Circuit Breakers for Phonographs, of which the following is a specification.

My invention relates to mechanism for 10 starting and stopping a phonograph motor automatically, and it consists in an automatic switch adapted to be operated by any free tone arm to close and open the motor circuit. In the embodiment shown it may 15 be used with any make of motor or tone arm. I have shown my invention embodied in a phonograph mechanism in which the starting and stopping of the rotation of the record table is caused by the closing and 20 opening of the circuit which supplies current to energize the motor by means of which the record table is rotated. My invention consists primarily in an automatic switch which is constructed and arranged to be 25 operated in a very simple manner without the use of electromagnets or other auxiliary mechanism to open and close it.

My invention will be understood by reference to the drawings, in which—

30 Figure 1 is a side elevation of a mechanism embodying my invention, the support upon which the various parts are mounted being in section.

Fig. 2 is a plan view in which the support 35 is broken away as well as a portion of the rotary table and record so as to show the controlling mechanism in plan.

Fig. 3 is an enlarged detail showing the 40 automatic switch mechanism and its relation to the other parts, and

Fig. 4 is a section on line 4—4 of Fig. 3. 45 1 is the support on which is mounted the tone arm 2 which is of usual character except that it is provided with a hanger 3 the lower end of which carries a link 4 connected to the circuit-breaking lever 5. Below the support is hung a frame 6 (see Fig. 2) in which is supported a shaft 7 carrying at its upper end the record table 8. 9 is a record placed on said table. 10 is a motor 50

which may be of any ordinary construction, preferably one of a kind now well known as a universal motor which will operate either by direct or alternating current. On the motor shaft is mounted a pulley 11 around which runs a belt 12 connecting with a pulley 13 on a shaft 14 on which is a worm 15. This worm engages with a worm gear 16 carried by the shaft 7 of the record table. By this means the record table is 55 rotated. The shaft 7 carries a worm 17 which meshes with a worm gear 18 on shaft 19 suitably supported by the frame 6 and carrying at its further end a worm 20 meshing with a gear 21. The construction and 60 arrangement of these parts is such that a very slow speed is imparted to the gear 21 in the direction of the arrows.

This gear 21 is mounted on a stud 22 which is supported in the frame 6. It has 70 a shoulder 23 which rests on the frame 6 and its lower end which passes through the frame is threaded and held in place by a nut 230. Resting on the frame 6 and around the stud 22 is a bushing 220 on a flange from 75 which rests the gear 21. An arm 34, carrying at its end a block 25 of insulated material, also is mounted to turn on the bushing 220. Above the arm 34 and compressed between it and the collar 36 is a 80 helical spring 35. The collar 36 is attached to the bushing 220 by a set screw 37. This construction is such that a frictional engagement exists between the arm 34 and the gear 21 such that the movement of the gear 85 will tend to carry with it the arm.

The lever 5 is also mounted to turn on the stud 22 and held by a collar pinned or otherwise attached to the top of the stud. To the short arm of the lever 5 is mounted 90 a block of insulating material 31. The block 25 has a binding screw 26 which connects electrically with a contact 29 and the block 31 has a similar screw 32 insulated from the arm 5, which connects electrically with the 95 contact 30. These contacts are preferably made of platinum. Between the bottom of the hub portion of the arm 5 and the top of the collar 36 is a light wire spring 38 one end of which engages the block 25 and the other 100

end the block 31 or the end of the lever 5 adjacent thereto, the purpose of this spring being to keep the contacts 29 and 30 normally in contact.

5 The circuit from the source of electricity comprises the wire 27, screw 26, contact 29, contact 30, screw 32, wire 28, thence to and through the motor back to the source. The wires are loose and flexible to allow for jar 10 in the operation of the machine.

As the various parts marked 39 are merely used for regulating the speed of rotation of the rotary table and are common to various machines of this kind and form no part of 15 my invention, they are not described.

It will be seen that any separation of the contacts 29 and 30 will break the circuit which feeds the motor, and this separation is possible because the contacts are mounted 20 on the two separately controlled arms 5 and 34. One of these arms 5 is operated by the tone arm and the other by the gear 21 with which it is held in frictional contact by the spring 35. The parts are so proportioned 25 and arranged that while the gear is constantly moving in the direction of the arrow it will carry with it the arm 34 and its contact 29. The needle will at the same time be moving in the spiral groove in the record 30 and the groove will draw the tone arm constantly towards the centre of the record, the tone arm continually moving the arm 5 so that its contact 30 will follow after the contact 29 in engagement with it. When, however, 35 the end of the spiral groove in the record is reached the tone arm will stop its movement and hence the arm 5 and its contact 29 will stop while the gear 21 and arm 34 will continue to move sufficiently to break 40 the contact between 29, 30, and cut off the current from the motor.

The tone arm is then swung back off the record and the record changed. The moving of the tone arm onto the new record closes 45 the contacts and the motor is again started and runs as before until the movement of the tone arm ceases.

It will be seen that the mechanism is simple and costs but little to build, and will not 50 easily get out of order, and it will be evident to one skilled in the art that my invention may be otherwise embodied.

The link 4 is shown provided with several 55 perforations 41 and is connected to the hanger 3 and lever 5 by studs 42 and 43, respectively. This enables assembly of the apparatus to be varied according to the type 60 of cabinet to be used, so that, for example, the tone arm may be placed on the middle of the rear of the cabinet as shown in the drawing or in one corner thereof or elsewhere as is most convenient.

What I claim as my invention is:—

1. In a device of the kind described, a 65 movable arm, a motor, a circuit for said

motor comprising a circuit breaker one member of which is attached to said movable arm to be moved thereby and the other member of which is mounted to be operated by said motor, whereby when said movable arm is given its normal movement the members of said circuit breaker will contact to maintain a closed circuit through said motor and when the normal movement of said movable arm ceases the circuit will be broken 75 and the motor will stop.

2. In a device of the kind described, a tone arm, a record table, a motor to rotate said record table, a circuit for said motor comprising a circuit breaker, one member of which is connected to said tone arm to be moved thereby, the other member being mounted to be operated directly by said motor.

3: In a device of the kind described, a tone arm, a record table, means for rotating said record table comprising an electric motor, a movable member operated by said record table, a circuit for said motor comprising a circuit breaker, one member of which is in frictional contact with said movable member to be moved thereby, the second member of said circuit breaker being mounted to be operated by said tone arm, said movable member and said tone arm having normally 95 a uniform movement with relation to each other whereby when said tone arm is given its normal movement due to the record on the record table, the members of said circuit breaker will remain in contact, but when said record ceases to operate said tone arm, the member of the circuit breaker connected to said tone arm will separate from the other member thereof and break the circuit through the motor.

4. In a device of the kind described, a record table, a shaft therefor, a motor connected to said shaft, a circuit for said motor comprising a circuit breaker, a rotary member and means for operating it connected to said record table shaft, one of the members of said circuit breaker being in frictional contact with said rotary member whereby it may be moved by said rotary member, a tone arm adapted to be moved toward the centre 110 of said record table, the second member of said circuit breaker being connected to said tone arm to be moved thereby, the connection between said rotary member and said record table shaft being such that its member of the circuit breaker and the tone arm member of the circuit breaker will travel at equal speed while said tone arm is moving toward the centre of the record table, and when said tone arm ceases so to move said first member 115 of said circuit breaker will separate from said second member and open the motor circuit and the motor will stop.

5. In a device of the kind described, a shaft carrying a record table and means for 130

rotating it comprising an electric motor, a circuit for said motor comprising a circuit breaker, a rotary gear connected to be operated by said motor, one member of said circuit breaker being mounted in frictional contact with said gear to be moved thereby, a tone arm adapted to be moved by the spiral

grooves of a record on said record table toward the centre of said record table, and a lever connected to said tone arm, the second member of said circuit breaker being mounted on said lever. 10

JOSEPH JANES.
